UNITED STATES PATENT OFFICE.

JOSEPH LEDERER, OF NEW YORK, N. Y.

DESIGN FOR A GAS-LAMP HOUSING.

47,080.

Specification for Design.

Patented Mar. 9, 1915.

Application filed December 11, 1914. Serial No. 876,739. Term of patent 7 years.

To all whom it may concern:

Be it known that I, JOSEPH LEDERER, a citizen of the United States, and a resident of the borough of Manhattan, city, county, and State of New York, have invented a new, original, and ornamental Design for a Gas-Lamp Housing, of which the following is a specification, reference being had to the accompanying drawing, forming part thereof.

The figure is a perspective view of a gas lamp housing, showing my new design.

I claim:

The ornamental design for a gas lamp housing, as shown.

JOSEPH LEDERER.

Witnesses:

PATRICK A. BOLGER,
ENDA TANNER.
